UNITED STATES PATENT OFFICE.

KNUTE H. ANDERSON, OF CHICAGO, ILLINOIS.

RUBBER-HEEL HOLDER.

Application filed July 7, 1926. Serial No. 120,955.

This invention relates to shoes and more particularly to a fastener for a detachable heel lift.

One object of the invention is to provide a fastener which may be securely attached to the body portion of a heel and serve to firmly but releasably hold a detachable heel lift of rubber or any other desired material in engagement with the shoe heel.

Another object of the invention is to so mount the fastener or anchor for the detachable lift that sockets forming a portion thereof will be embedded in the body portion of the heel and firmly held in place by a cover plate secured against the under face of the heel.

Another object of the invention is to permit a detachable rubber heel lift of a conventional construction to be secured without it being necessary to alter the same.

This invention is illustrated in the accompanying drawing, wherein

Figure 1 is a vertical sectional view through a heel showing the detachable lift secured thereto by means of the improved fastener;

Fig. 2 is a bottom plan view of the heel with the fastener or anchor applied thereto;

Fig. 3 is a fragmentary bottom plan view of the shoe heel showing one of the sockets embedded therein, and

Fig. 4 is a transverse sectional view taken on the line 4-4 of Fig. 3.

The detachable heel lift 1 represents a rubber heel of a conventional construction which is secured against the under face of a shoe heel 2 by machine screws 3 passed through the lift, as shown in Fig. 1, and screwed into sockets 4 embedded in the heel.

2. In the present illustration three securing screws are employed and are received in a corresponding number of sockets, but it will be understood that any number of screws and sockets may be provided according to the size of the rubber heel. The shoe heel 2 may consist of a solid block of wood or fiber covered with leather or any other suitable material or it may be formed of leather and consist of a suitable number of

lifts nailed or otherwise secured to each other in the usual manner. It will also be understood that the ground-engaging lift 1 instead of consisting of a rubber heel may be formed of any other suitable material as this invention relates to the anchor by

means of which the detachable ground-engaging lift is secured to the heel.

The sockets 4 which form a portion of the anchor are externally threaded and screwed into pockets 5 drilled from the under face of the heel, and these sockets are formed with threaded bores 6 to receive the securing screws 3 and with longitudinally extending grooves 8 through which headless nails 9 are driven after the socket is in place. From an inspection of Fig. 4, it will be seen that the nails, when driven into place, extend into the body of the heel at opposite sides of the sockets and will serve to prevent rotation of the sockets.

The sockets will, therefore, be very securely held in place as they are screwed into the pockets and locked by the nails. After the sockets have been fitted into their pockets, a cover plate 10 is placed against the under face of the heel and secured by a suitable

number of screws 11 which are passed through openings formed in the cover plate and screwed into the body portion of the heel. The screws 11 serve to very securely hold the cover plate in place but permit it to be removed when necessary. Openings 12 are formed in the cover plate and register with the threaded bores of the sockets 4 so that the securing screws 3 may be passed through the cover plate and screwed into the sockets.

When the rubber lift is secured to the heel by the screws 3, it will be very firmly attached and will not be liable to work loose and in addition it is not liable to be wrenched loose if a curb or other obstruction is struck by the heel when walking. When, however, the rubber lift is worn out, the screws may be easily removed and a new lift quickly substituted as it is not necessary to make adjustments to the lift other than trimming it to the proper size about its edges. It will be understood that rubber heels may be applied to the shoes at the factory with these improved fasteners and that the sockets and cover plates may be sold as a separate article of manufacture so that they may be employed by a shoemaker when applying rubber heels to shoes not previously equipped with them. When applied by a shoemaker, it is merely necessary to place the cover plate against the under face of a heel prepared to receive rubber lifts and after marking the places for the sockets

by a pencil or other implement passed through the openings 12 drill the pockets in the heel and then apply the sockets and cover plate and secure the cover plate by 5 the screws 11.

Having thus described the invention, I claim:

Means for removably securing an element to a support, said means comprising an externally threaded socket to be screwed into a pocket formed in the support, said socket having a threaded bore and formed with longitudinally extending external grooves 10 intersecting its threads, pins to be embedded 15 in the support adjacent the pocket and of

greater diameter than the grooves whereby portions may be received in the grooves of the socket to prevent rotation of the socket, a cover plate adapted to be removably secured against the face of said support between the support and element to be secured and formed with an opening registering with the bore of said socket, and a screw to be passed through the element to be supported and through the opening in the cover 20 25 plate and screwed into said socket to removably hold the element in place.

In testimony whereof I affix my signature.

KNUTE H. ANDERSON. [L. S.]
